(57) **CLAIM**

The ornamental design for a template for cutting quilting fabric, as shown and described.

DESCRIPTION

FIG. 1 is a top surface view of my template for cutting quilting fabric showing both solid and dashed lines associated with placement lines for the process of precisely cutting pieces of fabric useful in quilting; and wherein the solid and dashed lines are symbols used as measuring and visual guides. The dashed lines are not for illustrative purposes, but rather indicate stitching locations in different configurations as visual aids for a quilter using my invention of a template for cutting quilting fabric;

FIG. 2 is a bottom surface view of my template for cutting quilting fabric design showing, in reverse position, the top surface lines and guidance symbols when viewing such bottom surface through the clear acrylic of the template for cutting quilting fabric. Otherwise, the bottom surface view is flat and lacking in any ornamentation.

FIG. 3 is a right hand side edge view of my template for cutting quilting fabric with the left edge view being essentially the same;

FIG. 4 is a top surface view of my template for cutting quilting fabric design and includes the guidance lines of FIG. 1 with the addition of numbers that indicate stitching locations in different configurations as visual aids for a quilter using my template for cutting quilting fabric design invention; and, FIG. 5 is a top edge view of my template for cutting quilting fabric with the bottom edge view being essentially the same.
